US00D714787S

(12) **United States Design Patent**
Matsuoka

(10) **Patent No.:** **US D714,787 S**
(45) **Date of Patent:** **** Oct. 7, 2014**

(54) **HANDHELD DEVICE**(71) Applicant: **hiku labs, inc**, San Jose, CA (US)(72) Inventor: **Yoshimichi Matsuoka**, Cupertino, CA (US)(73) Assignee: **Hiku Labs, Inc.**, San Jose, CA (US)(**) Term: **14 Years**(21) Appl. No.: **29/466,914**(22) Filed: **Sep. 12, 2013**(51) LOC (10) Cl. **14-02**

(52) U.S. Cl.

USPC ..... **D14/426**(58) **Field of Classification Search**

USPC D14/420, 426-430, 453; 235/462.01, 235/462.11, 462.43, 462.45, 462.49, 235/472.01, 385, 454; 382/313, 321, 318, 358/473; 250/215, 216; D26/37-50, D26/24; 362/157, 158, 171-174, 183-208

Primary Examiner — Susan Moon Lee(74) *Attorney, Agent, or Firm* — Fenwick & West LLP(57) **CLAIM**

The ornamental design for a handheld device, as shown and described.

DESCRIPTION

FIG. 1 is top perspective view of a handheld device;
FIG. 2 is a bottom perspective view thereof;
FIG. 3 is a front perspective view thereof;
FIG. 4 is another front perspective view thereof;
FIG. 5 is a front elevation view thereof;
FIG. 6 is a left side elevation view thereof;
FIG. 7 is a right side elevation view thereof;
FIG. 8 is a bottom view thereof;
FIG. 9 is a top plan view thereof; and,
FIG. 10 is a rear elevation view thereof.

1 Claim, 10 Drawing Sheets(56)
